UNITED STATES PATENT OFFICE.

JOHN H. UHRIG, OF BEVERLY, NEW JERSEY, ASSIGNOR TO UNITED STATES CAST IRON PIPE & FOUNDRY COMPANY, OF BURLINGTON, NEW JERSEY, A CORPORATION OF NEW JERSEY.

TRANSPORTING MECHANISM FOR PIPE-ANNEALING FURNACES.

Application filed December 28, 1926. Serial No. 157,450.

My invention relates to pipe annealing furnaces of the general type of that described in the patent to Anthony, 1,525,905, of February 10, 1925. In furnaces of this type centrifugally cast cast iron pipes are supported and transported through the annealing furnace by means of a train of overlapping rollers in the bights of which the pipes are supported and rotated and which rolls are formed with circumferential notches by means of which the pipes are intermittently transported to the successive bights of the roll train. As heretofore constructed the notches of the supporting rolls have been so formed that in the operation of transporting a pipe from the bight of two overlapping rolls to the next succeeding bight the pipes roll with accelerated velocity and come in contact with the succeeding rolls while moving with considerable speed, as a result of which I have found that a considerable percentage of the pipes passing through the annealing furnace are bent and deformed and the object of my present invention is to provide improved means for transporting the pipes from the bight of one pair of rolls to the next succeeding bight in such a manner that no blow is struck and the tendency to deform the pipes is therefore avoided. A further object of my invention is to maintain the pipes in rotation as they pass from the bight of one pair of rolls to the next bight, this being important as tending to overcome the tendency of the heated pipes to sag out of shape as they may do if maintained in one position for an appreciable length of time; and a further object of my invention is to so angularly arrange the transporting notches of the rolls that the work of raising the pipes from the positions they occupy when lying in the notches to the positions they occupy on the cylindrical surfaces of the rollers will be distributed throughout the length of the roll train.

My invention consists, in the first place, in forming the notches in the rolls with two pipe retaining crests whereby the pipe is maintained in the notches while being transported from one to the next succeeding bight of the roll train and prevented from rolling with accelerated speed in the contact with the next succeeding rolls. My invention further consists in forming the notches between the crests thereof with a greater curvature than that of

the pipes to be supported and transported by the rolls so that, as the notches are moved from pipe receiving to pipe delivering positions, the pipes will roll over their curved surfaces and thus be maintained in rotation; and a third feature of my invention is, in a roll train having the features above noted, to arrange the notches at progressively different angles to a fixed plane so that the different pipes supported on the train will be lifted at different times and the work of lifting the pipes shall be distributed instead of concentrated, as would be the case if all the pipes were lifted at the same time.

My invention will be best understood as described in connection with the drawings, in which—

Figure 1 is a sectional longitudinal elevation through an annealing furnace provided with my improved pipe supporting and transporting mechanism with the pipe transporting mechanism shown in non-sectional elevation excepting only one sectional detail, and

Figures 2 to 11 are views showing in connection with the three rolls, F, F¹ and F², the progressive operation of the rolls in rotating and transporting the pipes from one to the next succeeding bight of the roll train.

A indicates the furnace; A¹ the entrance through which the pipes are introduced; A² the outlet passage through which the pipes are delivered and A³ a depending bridge wall located in the furnace. B indicates tracks which support the roll train carriage C through its wheels C¹. D is a shaft running longitudinally through the carriage and driven by any convenient mechanism, which shaft, as shown, is provided with a series of worms D¹, which worms drive the roll shafts indicated at E, E, etc., through the worm wheels indicated at E¹. F, F¹, F², etc., are the pipe supporting rolls secured on the shafts E. In all the above mentioned features, except in the special construction of the notches in the rolls F, the apparatus is substantially the same as that of the Anthony patent above mentioned.

G, G, etc., are the notches formed in the rollers, which notches, by my novel construction, are formed with two crests G¹ and G², where they merge into the circumference of the rolls and are formed with a concavely curved portion G³ lying between the crests,

the curvature of which is greater than that of the pipes indicated at H, which are supported and transported by the roll train.

The operation of my improved mechanism 5 is illustrated in Figs. 2 to 11. In Fig. 2 the pipe is shown as supported in the bight between the rolls F and F¹ with the crests G² of the notch in the roll F¹ just coming into registry with the supported pipe H. Figs. 10 3, 4 and 5 illustrate the action of the rolls in gradually lowering the pipe H into the notch in rolls F¹. Fig. 6 shows the pipe as supported in the notches of the rolls F¹ and Figs. 7 and 8 showing the work performed 15 by the rolls F¹ in transporting the pipe from the bight between the rolls F and F¹ to the bight between the rolls F² and F³ and it will be observed that in passing from the position shown in Fig. 6 to that shown in Fig. 8, 20 the pipe H will gradually roll from the position in which it lies close to the crest G¹ to the position where it lies close to the crest G² and is brought in contact with the surface of the roll F². Figs. 9, 10 and 11 illustrate the further work performed in lifting 25 the pipe from the position shown in Fig. 8 to the position shown in Fig. 11.

As shown in Fig. 1 the notches of each succeeding pair of rolls are arranged at progressively different angles to a fixed plane so that the work of lifting the pipes from the position shown in Fig. 8 to that shown in Fig. 11 is distributed throughout the roll train with the result, as I have stated, of 30 making this work a constant instead of an intermittent burden on the driving mechanism.

Having now described my invention, what I claim as new and desire to secure by Letters Patent is:

1. In an annealing furnace for cast iron pipes having means for supporting, rotating and progressively advancing the pipes consisting of a multiple series of overlapping

rotating cylindrical rollers having notched peripheries whereby a pipe resting in the bight of one pair of overlapping rollers is transferred to the next succeeding bight, the formation of said notches with a pipe retaining crest at both ends thereof so as to retain the pipe in the notches as it is transferred from one to the next succeeding bight and prevent it from rolling with accelerated speed into contact with the next succeeding rollers. 45

2. In an annealing furnace having the features of claim 1 the formation of the roller notches with a concave curved surface the radius of which is greater than that of the circumference of the pipes to be held therein 60 so that the pipes as they are transported in the notches from one bight to the next will roll slowly on the surfaces of the supporting notches.

3. In an annealing furnace for cast iron pipes having means for supporting, rotating and progressively advancing the pipes consisting of a multiple series of overlapping rotating rollers having notched peripheries whereby a pipe resting in the bight of one 65 pair of overlapping rollers is transferred to the next succeeding bight, the formation of said notches with a pipe retaining crest at both ends thereof so as to retain the pipe in the notches as it is transferred from one to the next succeeding bight and prevent it from rolling with accelerated speed into contact with the next succeeding rollers, said notches being also formed with concave supporting surfaces of greater curvature than the circumference of the pipes to be supported thereon and the notches of successive rollers being disposed at progressively different angles to a fixed plane so as to equalize the strain of lifting the pipe from the bottom to 75 the crests of the supporting notches. 80

JOHN H. UHRIG.
